UNITED STATES PATENT OFFICE

2,197,488

COIN CONTROL DEVICE

Charles R. Spare and Charles H. Lapsley,
Philadelphia, Pa.

Original application May 25, 1937, Serial No. 144,654. Divided and this application November 2, 1937, Serial No. 172,350

1 Claim. (Cl. 194—88)

Our invention relates to a new and useful coin control device, this application being a division of our Patent #2,147,320 granted February 14, 1939, on a Vending machine.

5 Our invention still further relates to a coin
control device which is extremely simple in its
construction thus greatly reducing the cost, and
one which, while designed for particular coop-
eration with the vending machine disclosed in our
10 co-pending application, is nevertheless also
adapted for use in connection with other vending
or dispensing devices.

or dispensing devices.

Our invention still further relates to a coin control involving various simple and mechanical operations without the use of any springs or other parts that may get out of order and need servicing or repairs.

The details of construction and manner of operation of our novel coin control device will be more clearly understood from the following specification and the accompanying drawings in which:

Fig. 1 represents a fragmentary top plan view of a coin control device embodying our invention shown applied to a portion of the casing of the vending machine in connection with which it is to be used.

Fig. 2 represents on a greatly enlarged scale a vertical section on line 2—2 of Fig. 1.

30 Fig. 3 represents a section on line 3-3 of Fig. 2.
Fig. 4 represents a section on line 4-4 of Fig. 2.
Referring to the drawings in which like refer-
ence characters indicate like parts, 6 designates
the permanent top wall of the casing or cabinet
35 of a vending machine to which is suitably hinged
at 7 the main cover 8, said cover 8 being prefer-
ably fastened by the lock 10 so that, when the
lock 10 is opened, the entire cover 8 can be swung
open along the hinge 7 to afford complete access
40 to the interior of the cabinet. To the main
cover 8 is hinged at 12 the small, delivery door 14
which is to be opened when the coin control
mechanism is operated to permit withdrawal of
the merchandise being dispensed. The door 14
45 is preferably provided with the transparent por-
tion 16.

The main cover 8 extends over a substantial part of the top wall 6 to cover a corresponding opening made therein so that, when the cover 8 is removed by opening the lock 10, the contents of the cabinet can be replenished. The cover 8 overlaps the rear portion of the top wall 6 as best seen in Fig. 1 and is provided with a humped portion 8x which houses the coin control mechanism. The door 14, as will be seen from

Fig. 1, is cut out of the body of the main cover 8 so that the small door 14 can be opened by operation of the coin control mechanism to permit removal of a bottle or the like from the cabinet after the proper coin has been deposited. The transparent portion 16 serves to enable the purchaser to see what kind of drink or confection is in registration with the door before depositing the coin so that the purchaser may manipulate the parts to bring into registration the particular type of confectionary desired. 5 10

The coin 18 is dropped through the slot 20 into a coin compartment 22, carried by the rocker arm 34. The coin compartment 22 is provided with the upper and lower openings 23 and 25 respectively of a predetermined size. If the coin is too small it will drop clear through the compartment 22, and if it is too big it cannot enter the compartment 22, and in either event it falls out onto the inclined chute or guideway 24 to be 20 discharged through the coin return 26. A coin of the proper size is retained in the compartment 22 so that, when the lever 28 which is pivoted at 28x to the wall 30x is moved in the direction of the arrow 38, the lug 32 carried by the lever 28 engages the edge of the coin 18 and interlocks the operating lever 28 with the rocker arm 34, which is also pivoted at 34x between the walls 30x and 31x it being understood that in the absence of a coin 18 in the compartment 22, the lever 28 can be reciprocated without engaging with or in any way actuating the rocker arm 34, the size of the lug 32 being such as to clear the rocker arm 34 in the absence of a coin the edge of which projects beyond the width of the compartment 22. The lug 32 moves in the slot 32x formed in the partition 30x. The movement of the lever 28 from the position indicated at A to the position indicated in dotted lines at B moves the rocker arm 34 from its original position at C to that indicated in dotted lines at D. This moves the pin 36 at the lower end 38 of the rocker arm 34 through the horizontal slot 40 and up the inclined slot 42. As the pin 36 travels in the inclined slot 42 it pushes the operating link 44 in the direction of the arrow 43. The operating link 44 is slidably connected by the pin 36 to the lower end of the arm 38 and the other end of the link is suitably pivoted in the position shown in Fig. 1 to any suitable support within the cabinet or to a portion of the top or side wall thereof (in a manner not shown) so as to have the shoulder 46 thereof engaging the rear edge of the door 14, whereby the movement of the pin 36 in the slot 42 will bring the shoulder 46 of the link 44 50

to bear against the adjacent edge of the door 14 and thus raises it from the closed position shown at E to the partially open position shown at F. This position of the door 14 does not permit withdrawal of the merchandise until the purchaser has pushed the door completely open from the position shown in F to which it was automatically opened by the movement of the lever 28 and rocker arm 34 to the second fully opened position shown at H. When the door 14 reaches the fully opened position at H, it exerts a pull on the rocker arm 34 in the direction of the arrow 50 thus causing the rocker arm 34 to clear the lever 28 when the latter is at the extreme limit of its motion in the position B. This releases the coin 18 interlocked between the lever 28 and the rocker arm 34 and permits it to drop into a coin box 52. It will be noted that the coin compartment 22 is flanked by the partitions 31x and 30x from which are inwardly turned flanges 54 and 56 respectively on which the coin 18 rides during its travel from the point at which it is originally dropped until it reaches the coin box 52. It will also be seen that the lever 28 travels in the slot 29 in the cover 8 the length of which limits the movement of said lever, and that the upper end of the wall 22x of the coin compartment 22 is extended upwardly and deflected at 35 so that, when the rocker arm 34 is in the operative position shown in dotted lines at D, the deflected portion will also assume the position shown in dotted lines in which it obstructs the opening 20 to prevent the deposit of another coin until the rocker arm 34 is returned to the position C and the lever 28 is returned to the position shown at A.

It will thus be seen that we have devised a

very simple and efficient form of coin control which only has the operating lever 28, the rocker arm 34 and the complementary slotted rocker arm 44, whereby the door 14 can be opened, and whereby as soon as the door 14 is released after the merchandise has been removed it will drop by its own weight from the position at H into the closing position at E whereupon the pin 36 moves down the inclined slot 42 and into the horizontal slot 40. This returns the rocker arm 34 from the position at D to the position at C thus permitting the deposit of another coin through the slot 20. The operating lever 28 can be returned to the position A manually or a suitable spring can be employed for that purpose. 15

Having thus described our invention what we claim as new and desire to secure by Letters Patent is:

In a coin control mechanism, a casing, an operating lever pivoted at its lower end to said 20 casing and having its upper end movable in a slot in the top of said casing, a lug carried by said operating lever, a rocker arm pivoted at its upper end to said casing, a coin compartment carried by said rocker arm in spaced relation from said 25 lug so that the latter clears said compartment in the absence of a coin therein, a link having a horizontal slot and an inclined slot formed therein and a pin carried by the lower end of said rocker arm and normally resting in said horizontal 30 slot, said pin being adapted to ride in said inclined slot when said rocker arm is operated by said operating lever to actuate said link in accordance with the movement of said rocker arm. 35
